UNITED STATES PATENT OFFICE.

CARL ARNO MEILICKE, OF HANLEY, CANADA.

CALCULATING-MACHINE.

No. 823,426.

Specification of Letters Patent.

Patented June 12, 1906.

Application filed June 9, 1905. Serial No. 264,417.

To all whom it may concern:

Be it known that I, CARL ARNO MEILICKE, a citizen of the United States, and a resident of Hanley, Assiniboina, North-West Territories, Dominion of Canada, have invented a new and Improved Calculating-Machine, of which the following is a full, clear, and exact description.

This invention relates to calculating-machines.

The object of the invention is to produce a simple mechanism which will enable charges or accounts of different kinds to be easily computed.

The invention is especially applicable in computing interest upon notes, but is capable of use in various connections for the general purposes stated.

The invention consists in the construction and combination of parts, to be more fully described hereinafter and definitely set forth in the claims.

Reference is to be had to the accompanying drawings, forming a part of this specification, in which similar characters of reference indicate corresponding parts in all the figures.

Figure 1 is a plan of the machine, the central portion thereof being broken away, as will appear. Fig. 2 is a transverse section taken substantially upon the line 2 2 of Fig. 3, certain parts being broken away, as will appear. Fig. 3 is a vertical central section through the machine, the body of the machine being broken away, as will appear. Fig. 4 is a vertical transverse section taken substantially upon the line 4 4 of Fig. 3. Fig. 5 is a vertical section taken through the wall of the machine and illustrating means for holding the drum to facilitate the reading of the results. Fig. 6 represents a portion of the table carried by the drum and a calendar which co-operates therewith, and Fig. 7 is a similar view representing a portion of a scale which co-operates with the calendar and table shown in Fig. 6.

Referring more particularly to the parts, 1 represents a case or barrel of substantially cylindrical form disposed with its axis horizontal, said casing being formed below into a suitable base 2, adapted to rest upon a horizontal support, such as a table or shelf. This barrel 1 is formed in two sections comprising a body 3 and a removable bonnet or cover 4, the said bonnet being attached to the body by bolts or rivets 5, passing through alined ears 6, as indicated most clearly in Fig. 2.

The ends of this barrel 1 are formed into heads 7 and 8, which are of obtuse conical form, as indicated. At a suitable point, preferably upon the upper side, the wall of the case or barrel 1 is provided with an elongated slot or sight-opening 9, which passes longitudinally of the case, as indicated. Preferably just below this sight-opening 9 the wall of the case is provided with a longitudinal groove or recess 10, in which a scale 11 is inserted, as indicated. The purpose of this scale will appear more fully hereinafter.

Preferably above the sight-opening 9 a longitudinal groove or recess 12 is provided which is similar to the groove 10 aforesaid, but of greater width, as indicated. This groove is adapted to receive a slide 13, the purpose of which will be described more fully hereinafter.

Within the case 1 a drum 14 of cylindrical form is rotatably mounted, the same being rigidly carried upon a shaft or axle 15. This axle passes axially through the heads 7 and 8 and just without the head 7 is provided with a thumb-head 16, which enables the drum to be rotated as desired.

Rotatably mounted upon the shaft 15 a wheel 17 is provided, said wheel having a disk-body 18 and a circumferentially-disposed flange 19, said flange being of the same diameter as the drum 14 and lying adjacent to the extremity of said drum, as indicated. To the body 18 a hub 20 is rigidly attached, which is formed with a tubular neck 21, within which the aforesaid shaft 15 lies, as indicated. At a suitable point a circumferential groove 22 is formed in the shaft 15, and a set-screw 23 is inserted in the neck 21, which is received in the said groove and locks the wheel 17 against longitudinal movement with respect to the shaft, as will be readily understood.

As indicated most clearly in Fig. 3, the extremity of the hub 20 projects beyond the head 8 and receives over it a sleeve 24, which is formed integrally with a thumb-head 25. This thumb-head enables the wheel 17 to be rotated at will, and to this end the bore of the sleeve 24 is provided with longitudinal grooves 26, in which grooves oppositely-disposed tongues 27 are received, the said tongues being formed upon the outer side of the tubular extension of the hub 20, as indicated. From this arrangement it should now be understood that by rotating the

thumb-head 16 the drum 14 may be rotated, and by rotating the thumb-head 25 the wheel 17 may be rotated.

I provide means for locking the wheel and drum to each other in any position desired. For this purpose the thumb-head 25 is adapted to slide longitudinally upon the hub 20. At its inner extremity it is formed with a circumferentially-disposed collar 28. At a suitable point the tubular neck 21 of the hub is formed with oppositely-projecting ears 29, the said ears being formed with openings 30. The edges of these openings, which lie adjacent to the axis of the shaft, are oppositely beveled, so as to present angular edges or knife-edges 31. Opposite the openings 30 openings 32 are formed, which pass through the hub 20 and the disk-body 18 of the wheel 17, and through these aligning openings clutch-bars 33 pass. These bars on their faces, which lie adjacent to the knife-edges 31, are provided with V-shaped notches 34, which are adapted to receive the knife-edges, as indicated in Fig. 3. At their inner extremities the clutch-bars 33 project into the interior of the wheel 17, and at this point they connect pivotally with links 35. Near the periphery of the wheel 17 the disk 18 thereof is formed with posts 36, and to these posts clutches 37 are pivotally attached; the said clutches comprising laterally-bent arms, which terminate in the shoes 38, lying adjacent to the inner face of the periphery of the drum 14, as shown. In this connection it should be stated that the circumferential wall of the drum 14 projects beyond the head 39 thereof which lies adjacent to the wheel 17.

Through the aforesaid collar 28 a pair of oppositely-disposed set-screws 40 project, and the extremities of these set-screws are received in the rear faces of the outer extremities of the clutch-bars 33. From this arrangement it follows that when the thumb-head 25 is forced inwardly the clutch-bars 33 are also projected inwardly, the innermost notches becoming disengaged, as will be readily understood.

The inward movement of the clutch-bars will continue until the outer pair of the notches 34 come into alignment with the knife-edges 31, at which time the clutch mechanism will lock itself. When this occurs, the shoes 38 will have been forced outwardly against the inner face of the drum in such a way as to bring about a substantial frictional engagement therewith. When the thumb-head 25 is forced inwardly in this manner, the wheel 17 will be firmly locked to the drum, as will be readily understood.

Arrangement is made for normally maintaining the drum 14 in a certain position, which position would generally be called a "zero" position. For this purpose on the interior of the drum a counterweight 41 is placed, and this weight normally gravitates

to the lowest possible point, as indicated in Figs. 2 and 3, operating to maintain the drum in a corresponding position.

In order to insure that the drum will stop at exactly the zero position, I provide a finger 42, of resilient material, as indicated in Fig. 2, which is formed with a nib 43, received in a corresponding notch 44, the said notch being formed at the central line of the weight 41 on the outer face of the drum, as shown.

Upon the outer surface of the drum 14 I attach a card 45 or sheet of paper, upon which figures are arranged in tabulated form, so that the card constitutes a computing-table. The quantities tabulated will depend upon the purposes for which the machine is to be used. However, in all cases the figures upon the card will be divided into circumferential and longitudinal rows, as shown. Upon the outer face of the wheel 17 a computing-scale 46 is arranged circumferentially, and the entire length of this scale is formed in divisions which depend upon the character of the use to which the machine is to be put. In order to enable the figures of this scale to come accurately into alignment with the sight-opening 9, the periphery of the wheel 17 is provided with corrugations or rounded teeth 47, as indicated in Fig. 5, and these teeth are arranged so that they correspond in relation with the divisions on the scale 46. On the inner face of the case at a suitable point a detent-spring 48 is provided, formed with a tip 49, which is received in one of the recesses between the teeth 47. From this arrangement it should be understood that if the wheel were rotated slowly and intermittently the detent-spring 48 would tend to produce a step-by-step movement in which the divisions on the scale 46 would align successively with the sight-opening, and if the wheel were stopped in any position some one of the figures on the scale 46 would lie clearly in the opening 9.

The machine is especially adapted for computing the interest on notes. When used in this capacity, the scale 46 is provided with circumferential bands 50 and 51, which constitute a calendar, and the band 50 is divided into twelve principal divisions representing the months of the year, and a portion of this band 50 is formed with smaller divisions representing the days of each month. A corresponding arrangement is employed for the band 51; but the direction in which the bands progress is reversed.

The card upon the drum 14 is divided into three hundred and sixty-five divisions corresponding to the days of the year, and at the right of the card and at its edge which lies adjacent to the calendar figures are placed running from "0" to "365" in succession, so as to constitute the day-strip 52. Thus we have two bands upon which may be indi-

5 cated the months and dates of the months of the notes, while we have a strip which may indicate the number of days for which the note is to run. This relation is indicated in the scale shown in Fig. 7, which represents a portion of the scale 11, referred to above. The body of this scale is divided into sections representing the amounts of one dollar, two dollars, three dollars, &c., and each section 10 is itself divided into smaller divisions, adjacent to which the numbers "6," "7," "8," "9," and "10" are placed. These numbers correspond to different interest rates. The divisions of the sections correspond exactly 15 with the divisions measured longitudinally upon the card 45. The entire surface of the card 45 is divided off by circumferential lines and horizontal lines, and in the squares so formed numbers are placed which correspond 20 to certain interest rates and certain periods. Thus the number opposite the seventy-eighth day of the day-strip and opposite the "9" in the one-dollar section of the scale 11 would indicate the interest on one dollar at 25 the rate of nine per cent. for a period of seventy-eight days. In practice the dollar divisions upon the scale 11 would run successively up to one hundred, beyond which point they would be arranged in hundreds, 30 and afterward in thousands, progressing toward the left end of the drum, as indicated in Fig. 1.

From the arrangement described for the card 45 it should now be understood that 35 the interest on any amount for a given number of days may be readily computed. Suppose, for instance, that it were desired to find the interest upon one hundred and seventeen dollars for ninety days. The drum would be 40 rotated until the number "90" in the day-strip 52 appears in the sight-opening 9. Then looking upon the scale 11 in the "\$100" division and at the corresponding interest rate the amount of the interest for one hundred 45 dollars for the given time will appear in the sight-opening. The interest upon the seventeen dollars would be found in the same way, and these quantities added produce the result. The calendar 46 enables the interest 50 to be computed readily when the dates of making and of maturity of the note are known. Suppose that a note is dated January 19 and is to mature March 15, the interest rate being six per cent. and the amount 55 of the note seventy-five dollars. The wheel 17 would be rotated until the date "January 19th" on the calendar-band 50 comes opposite to the "0" on the card 45, as indicated in Fig. 6. It should be stated at this point 60 that the "0" on the card 45 would normally appear in the sight-opening 9. After the date "January 19th" is brought into alignment with the "0" on the card 45, as indicated, the thumb-head 25 would be pushed 65 inwardly so as to lock the wheel 17 to the

drum. The rim of the wheel would then be rotated in an upward direction—that is, so as to pass the months following January upon the band 50 in succession under the opening. Thus the month "February" and 70 the month "March" would pass until the date "March 15th" were reached. Opposite this date "March 15th" the number "55" will appear on the day-strip of the card, showing that such a note would be for a period of fifty-five days. The operator of the machine would now look in the dollar-section for "\$75," in the six-per-cent. division thereof, and would see just above in the sight-opening the interest amount for the given note. 80 While this method would be adopted for notes having different dates of making and maturity, another method would be adopted for computing the interest on a number of notes all having the same date of maturity. 85 In banks and similar institutions notes are constantly being computed under these circumstances. Suppose that the interest upon a number of notes is to be computed, the said notes maturing on February 10. The wheel 90 17 would be rotated until the date "February 10th" on the calendar-band 51 becomes opposite to the "0" mark. Having brought the wheel to this position, the thumb-head 25 is pushed in so as to lock the wheel to the 95 drum in the manner now well understood. Suppose now that the first note to be computed is dated "January 1st." The wheel and drum would then be rotated until the date "January 1st" on the calendar-band 51 appears in the sight-opening 9. If the note is for one dollar at seven per cent., in the sight-opening above the dollar-section in the seven-per-cent. division would be found the interest for this note. In the day-strip 52 would 100 be found the number "40," indicating that the note will have run forty days. The other notes would be computed in the same way, using the calendar-band 51. From this arrangement it will appear that the calendar-bands, arranged as they are in reverse order, enable the number of days to be computed quickly, counting in either direction, 105 from the present date.

In order to facilitate the manipulation of 115 the machine, I provide a small rack 53, which is preferably attached to the upper side of the case, as indicated, and in this rack the notes may be placed so as to enable them to be readily seen during the operation.

In the manner described the amounts of interest would be computed for fractions of a year. In order to facilitate the computations for even numbers of years—as two years, three years, four years, and so on—I provide 125 the scale or slide 13. This scale does not cooperate in any manner with the drum 14, but does cooperate with the scale 11, showing in tabulated form the interest amounts on notes for one, two, &c., to five years upon 130

one dollar, two dollars, three dollars, and so on. Thus upon this scale the interest on a note for two dollars at six per cent. for two years would be found by looking at the scale 5 11 in the two-dollar section. Above this scale is the six per cent. division, and in the two-year rate of the scale 13 would be found the interest amount for this time.

In computing the interest on notes running 10 for an even number of years and a fraction the interest for the fractional time would be computed by means of the drum and wheel, and this amount would be added to the interest amount taken from the scale 13, as will be 15 readily understood.

While I have described the machine in its adaptation to the purpose of computing the interest on notes, it is capable of various other uses. When used for other purposes, 20 as suggested, the character of the scales and tables would be changed to suit the particular units of measurement or requirements. Thus if using the machine for measuring lumber the day-strip 52 would represent the 25 number of pieces of lumber sold. The scale 11 would represent prices per thousand board feet and would contain characters indicating different kinds of lumber—thus “2” $\times$ “6”—“10” or “6” $\times$ “10”—“2,” and so 30 on. With this arrangement for the scales if it were desired to find the charge to be made for thirty pieces of lumber of two inches by six inches by ten feet at sixteen dollars per thousand the drum would be turned until 35 the figure “30” at the right end of the drum would appear in the sight-opening 9. Then on the drum opposite characters “2 $\times$ 6—10” would appear the number “300,” indicating the board feet in the thirty pieces. Now 40 turn drum until the figure “300” appears in the sight-opening at the right end. Then opposite 16, which represents the price per thousand, would be found on the drum the number “4800.” After pointing off three 45 decimal-places the price, four dollars and eighty cents, is obtained.

Having thus described my invention, I claim as new and desire to secure by Letters Patent—

50 1. In a machine of the class described, in combination, a case presenting a sight-opening, a drum containing tabulated figures rotatably mounted within said case, a computing-wheel coaxial with said drum and rotatably mounted within said case, a thumb-head adapted to rotate said wheel and mechanism actuated by said thumb-head for locking said wheel to said drum.

55 2. In a machine of the class described, in combination, a case having a sight-opening therein, a drum rotatably mounted within said case and carrying tabulated figures, a counterweight on said drum adapted to maintain the same in a normal position, a detent-pawl carried by said case and engaging

the face of said drum, said drum having a recess coöperating with said detent-pawl to maintain said drum in said normal position.

3. In a machine of the class described, in combination, a case, a drum carrying computing-tables and rotatably mounted therein, a wheel coöperating with said drum and rotatably mounted within said case, a thumb-head making a tongue-and-groove connection with the hub of said wheel, and affording means for rotating said wheel, and means actuated by the longitudinal movement of said thumb-head for locking said wheel to said drum.

4. In a machine of the class described, in combination, a case, a drum carrying computing-tables and rotatably mounted therein, a thumb head lying outside of said case and adapted to rotate the said drum, a wheel rotatably mounted within said case and co-operating with said drum, a thumb-head lying outside of said case and slidably mounted upon the hub of said wheel, means for locking said thumb-head and said wheel against relative rotation whereby said thumb-head affords means for rotating said wheel, a clutch between said wheel and said drum, and a connection between said clutch and said thumb-head for actuating said clutch.

5. In a machine of the class described, in combination, a case, a drum carrying computing-tables and rotatably mounted therein, a computing-wheel coöperating with said drum and rotatably mounted within said case, oppositely-disposed clutches between said wheel and said drum and adapted to lock the same together, links connected with said clutches, a thumb-head adapted to rotate said wheel and slidably mounted on the hub thereof, and clutch-bars carried by said thumb-head and connected with said links.

6. In a machine of the class described, in combination, a case, a drum carrying computing-tables and rotatably mounted therein, a computing-wheel rotatably mounted within said case, a clutch between said wheel and said drum, said wheel having a hub with laterally-projecting ears, said ears having guide-openings therethrough, clutch-bars projecting through said guide-openings and passing into the interior of said wheel, links connecting said clutch-bars with said clutches and a thumb-head attached to said clutch-bars and affording means for thrusting the same inwardly and a connection between said thumb-head and said wheel for rotating said wheel.

7. In a machine of the class described, in combination, a case, a drum carrying computing-tables and rotatably mounted therein, a computing-wheel rotatably mounted within said case and coöperating with said drum, clutches between said wheel and said drum, links affording means for operating said clutches, said wheel having a hub with

laterally-disposed ears having openings there-through, said openings presenting knife-edges, clutch-bars attached to said links passing through said knife-openings and presenting notches coöperating with said knife-edges, means for guiding said clutch-bars through said wheel, a thumb-head attached to said clutch-bars and affording means for rotating said wheel, said thumb-head being slidably mounted upon said hub and affording means for thrusting said clutch-bars inwardly to operate said clutches.

8. In a machine of the class described, in combination, a case, a drum carrying computing-tables and rotatably mounted therein, a wheel coöperating with said drum and rotatably mounted within said case, shoes carried by said wheel and adapted to engage said drum, links attached to said shoes and leading toward the hub of said wheel, a thumb-head slidably mounted on said hub

and affording means for rotating said wheel, and connections from said thumb-head to said links for operating said shoes.

9. In a machine for computing interest on notes, a table containing interest amounts arranged successively in numbered divisions corresponding to the days for which the notes may run, and a calendar coöperating with said divisions and comprising calendar-strips having the months and days indicated thereon, the indications on said strips being arranged in reverse order with respect to each other.

In testimony whereof I have signed my name to this specification in the presence of two subscribing witnesses.
